CORNICE

Elmer F. Rebholz, Chicago, Ill., assignor of one-third to James F. Barnes and one-third to Jean O. Reinecke

Application September 30, 1940, Serial No. 358,985

9 Claims. (Cl. 156—13)

This invention relates to a cornice, and more particularly to a window cornice of variable or adjustable depth.

An object of the invention is to provide a window cornice which may be arranged to extend any desired distance from the window frame. Another object is to provide a window cornice which may be used with any width of window. Still another object is to construct a cornice bracket which may be readily and easily packaged and handled. Yet another object is to provide in a window cornice a cornice board and supporting brackets therefor cooperatively arranged with the board to present an attractive appearance. A further object is to provide a substantially flat cornice bracket bendable at spaced portions along the longitudinal sides thereof. Still another object is to provide in a cornice bracket longitudinal channels for slidably receiving a cornice board, which channels do not interfere with the bending of the bracket.

Further objects and advantages will appear from the following specification and drawing, in which—

Fig. 1 is a perspective view of my improved window cornice in position on a window frame; Fig. 2 is a plan view of the cornice bracket blank; Fig. 3 is a perspective view of a corner member; Fig. 4 is a transverse sectional view taken along the line 4—4 of Fig. 1; and Fig. 5 is a vertical sectional view taken along the line 5—5 of Fig. 4.

As is well known, window cornices are used with windows of widely varying width and also arranged to extend different distances from the window frame. By this invention, a simple cornice construction is provided which is adapted for use with different sized windows and adapted to provide a cornice of variable depth.

Broadly, the cornice construction includes a cornice board and a pair of brackets supporting the board. The board may be of any suitable length, depending upon the width of the window, while the brackets may be arranged to provide the desired depth for the cornice.

In the specific embodiment of the invention described herein, a pair of brackets 10 and 11 are mounted on a window frame 12 and support between them a cornice board 13.

As seen particularly in Fig. 2, the blank from which the bracket 10 is formed may be a flat, flexible, inelastic, metallic strip 14, the strip being preferably composed of a soft bendable metal such as steel or a suitable alloy. If desired, other bendable materials may be used in place of the metal.

To the strip or body 14 of the bracket 10 are integrally secured a plurality of lugs 15 extending from the longitudinal sides 16 and 17 of the strip 14. The lugs are spaced apart along the sides of the strip. The lugs 15 may be made of

the same material as the body of the bracket, and, if desired, may be continuous therewith as shown. If this construction is used, the bracket blank, including the lugs, may readily be formed by merely stamping it from a suitable sheet of material.

An extension 18 is secured to one end of the strip 14, the extension being provided with apertures 19 and 20 and slots 21 and 22 communicating therewith. As seen particularly in Fig. 4, the extension 18 may readily be right angularly bent with respect to the body of the bracket to form a lateral flange 23. It is by means of this flange 23 that the bracket may be mounted upon a wall or window frame.

The lugs 15, being of soft material and readily bent, are turned inwardly to form longitudinal channels (Fig. 1) on the strip 14. The lugs may, of course, be turned inwardly towards either side 20 of the strip 14.

The surface of the strip 14 is preferably provided with a plurality of transverse scores 26 extending across the strip at each of the longitudinal portions thereof between the lugs 15. The scores 26 may consist of small grooves cut in the surface of the strip 14, and are preferably of sufficient depth to facilitate bending of the strip along the score lines.

The strip 14 may thus be bent transversely at any of the spaced longitudinal portions between the lugs 15. Preferably it is right angularly bent to form an end support 24 and a side portion 25.

The cornice board 13 may be of any desired composition or character. The board is usually made from wood or composition material such as that sold under the trade name "Masonite." It may, if desired, be painted, and may bear upon its face any suitable design (not shown) to increase the attractiveness of its appearance.

The opposite ends of the cornice board 13 are received within the longitudinal channels of the brackets 10 and 11, the board preferably being inserted into the bracket before the cornice is mounted on the window frame. The length of the cornice board will, of course, depend upon the width of the window to which the cornice is to be applied.

When the cornice is being assembled, the window may be measured and the board cut to the proper length. End boards 29 of material similar to that of the cornice board 13 may be slidably inserted into the channels of the end supports 24.

A corner member 30 of metal or other suitable material may be provided to cover the space between the cornice board 13 and the end boards 29. The corner member preferably comprises a rounded body 31 and flanges 32 and 33 right angularly disposed with respect to each other, the flanges 32 and 33 being adapted to be received

within the channels of the end supports 24 and side portion 25 of the brackets 10 and 11 beneath the cornice board 13 and end board 29.

The cornice assembly is mounted on the window frame by securing the flanges 23 of the brackets 10 and 11 to the headed screws 27 and 28 in the frame, the screws being received within the slots 21 and 22 to anchor the cornice in position.

The bracket 10 may be constructed in the form of an entirely flat member or with the extension 18 and the lugs 15 bent as heretofore described. In either event, the bracket is easily packaged and handled, and occupies but little space.

The cornice board 13 may be made in the proper length for the window to which the cornice is to be applied, or, if desired, may be made of a length greater than the width of any window with which it is expected to be used. In the latter case, when the cornice is to be assembled, the board must be cut to the proper length.

In assembling the cornice, the brackets 10 and 11 are first prepared for use, the extensions 18 being bent to form lateral flanges 23, and the lugs 15 being turned in to form the longitudinal channels in the brackets. The depth of the cornice desired is then determined, and the bracket bent along the line of the appropriate score 26. The width of the window is measured and the cornice board cut to proper length. The corner member 30, the cornice board 13, and the end boards 29 are then inserted in the channels in the brackets 10 and 11 in the manner shown in Fig. 1.

The cornice is thus completely assembled, and may be secured to the window frame by mounting the flanges 23 thereon.

The window cornice which is thus produced is extremely attractive in appearance, since the lugs 15, which retain the boards in position, provide a fluted appearance at the corners. The cornice board, bearing a suitable design, adds to the attractiveness. At the same time, the structure is extremely simple in both construction and assembly.

While there are shown and described certain embodiments of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

I claim:

1. A cornice of the character described comprising a cornice board, and a pair of brackets for slidably supporting said board, said brackets being bendable transversely at spaced longitudinal portions thereof to provide a cornice of variable depth.

2. A cornice of the character described comprising a cornice board, and a pair of brackets equipped with longitudinal channels for slidably supporting said board, said brackets being bendable transversely at spaced longitudinal portions thereof to provide end supports of variable depth for said cornice.

3. A cornice of the character described comprising a cornice board, and a pair of flat, flexible, inelastic, metallic strips equipped along the

longitudinal sides thereof with a plurality of spaced lugs extending therefrom, said lugs being turned inwardly to form channels for slidably receiving said board, said strips being right angularly bendable at the spaced portions thereof between said lugs to provide end supports for said cornice.

4. A cornice of the character described comprising a cornice board, a pair of flat, flexible, inelastic, metallic strips equipped along the longitudinal sides thereof with a plurality of spaced lugs extending therefrom, said lugs being turned inwardly to form channels for slidably receiving said board, said strips being transversely scored at the spaced portions thereof between said lugs and being bendable along the score lines to provide end supports for said cornice, and means adjacent the ends of said strips for mounting the same on a wall.

5. A cornice of the character described comprising a cornice board, a pair of flat, flexible, inelastic, metallic strips equipped along substantially the entire length of each of the longitudinal sides thereof with a plurality of spaced lugs extending therefrom, said lugs being turned inwardly to form channels for slidably receiving said board, said strips being transversely scored at the spaced portions thereof between said lugs and being right angularly bent along one of said score lines to provide end supports for said cornice, lateral flanges on said end supports for mounting the same on a wall, a pair of end boards slidably carried by the inwardly turned lugs on said end supports, and a pair of corner members mounted on said strips between the ends of said cornice board and said end boards.

6. A variable depth cornice bracket comprising a soft, flat, bendable metallic strip equipped with longitudinal channels thereon, and means on said bracket for mounting the same on a wall.

7. A variable depth cornice bracket comprising a flat, flexible, inelastic body, and a plurality of spaced lugs secured to said body along at least one of the longitudinal sides thereof, said lugs being turned inwardly to form a channel for slidably receiving a cornice board, said body being bendable along a transverse axis through any of the longitudinal portions thereof between said lugs.

8. A variable depth cornice bracket comprising a flat, flexible, inelastic, metallic body, and a plurality of spaced lugs integrally secured to said body along the longitudinal sides thereof, said lugs being turned inwardly to form longitudinal channels for slidably receiving a cornice board, said body being bendable along a transverse axis through any of the longitudinal portions thereof between said lugs.

9. A variable depth cornice bracket comprising a flat, flexible, inelastic, metallic strip equipped along substantially the entire length of each of the longitudinal sides thereof with a plurality of spaced lugs extending therefrom, said lugs being turned inwardly to form channels for slidably receiving a cornice board, said strip being transversely scored at the portions thereof between said lugs and being right angularly bent along one of said score lines to provide end supports for said bracket, and a lateral flange on said end support for mounting the same on a wall.
